DOOR LATCH OR CATCH FOR CAMERAS AND OTHER STRUCTURES

Henry M. Hendrickson, Rochester, N. Y., assignor to The Folmer Graflex Corporation, Rochester, N. Y., a corporation of Delaware

Application October 28, 1939, Serial No. 301,798

6 Claims. (Cl. 292—86)

This invention relates to a door latch or catch which, while of general application and may be employed on many different types of structures having doors, is particularly intended for use on photographic cameras to hold the door of the camera box or casing closed, yet permitting easy and positive operation in opening and closing the door.

In order that the principle of the invention may be readily understood, I have disclosed a single embodiment thereof in the accompanying drawings wherein—

Fig. 1 is a perspective view of the door latch or catch removed from the camera box or other article of use;

Fig. 2 is a view mainly in vertical section showing the latch or catch as used on a camera, the camera door being shown as open;

Fig. 3 is a view similar to Fig. 2, but showing the camera door closed;

Fig. 4 is a view similar to Fig. 1 but showing the latch or catch inverted, more clearly to illustrate the relationship of the various parts;

Fig. 5 is a perspective detail of the buffer bar of the latch or catch;

Fig. 6 is a vertical sectional view of the camera, showing the latch or catch forced downward under the influence of the plunger and the door as being pushed open by the buffer bar;

Fig. 7 is a vertical sectional view, showing the camera door held firmly closed;

Fig. 8 is a side elevation of the latch or catch;

Fig. 9 is a top plan view thereof; and

Fig. 10 is a bottom plan view thereof.

The latch or catch herein disclosed, although shown applied to a photographic camera to hold the door of the camera box or casing firmly shut, is applicable to the doors of numerous structures among which may be enumerated refrigerators, automobiles and cabinets for various uses.

In its simplest form, the latch or catch includes a body portion preferably of resilient metal, such as sheet steel, adapted to be secured to an inner face of the structure, the door of which is to be held closed or the opening of which door is to be initiated by the said latch or catch. Carried by said body is a spring pressed buffer bar which engages one face of a flange or formation of the door, and said latch body also has one or more lips or holding dogs to engage the other face of the said flange of the door. A plunger, the head whereof is accessible to be manually pushed, is mounted in the wall of the structure to which the latch or catch is secured, and in such manner that pressure thereon flexes the resilient body

portion of the latch or catch, and in so doing releases the lip or dog from engagement with the outer face of the flange or formation on the door, thereby permitting the said spring pressed buffer bar automatically to move the door slightly open, so that the door may then be readily grasped and moved by the hand of the user to full open position. Having thus generally described the structure and purpose of my invention, I will, without specifically limiting myself thereto, refer in detail to the construction of the selected embodiment of my invention.

I have chosen to represent the latch or catch as applied to a camera casing, but it is to be understood that while the invention is particularly applicable thereto, it may be used on various other structures, among which I have enumerated refrigerators, automobiles and cabinets as merely representative of a wide capacity of use.

Desirably the latch or catch is constructed of a single piece of metal, such as sheet steel, having a sufficiently spring-like or resilient nature and providing a body part receiving certain moving parts of the latch or catch. Referring more particularly to the figures showing only the latch or catch as an entirety, the body portion thereof is indicated generally at 20. It preferably has a flat surface 20a which is to be secured against an inner wall or part of the structure adjacent to the door thereof. The flat surface 20a of the latch is provided with a suitable number of openings 21, 21 for fastening the latch body to the camera box or other structure. At the termination of the flat surface 20a is a right angularly bent portion 21a which is pierced by an opening 22, preferably centrally positioned with respect to the outer edges of the right angled portion 21a. The said portion 21a is again bent at right angles as indicated at 22a, and the outer end or ends of the portion or portions 22a is or are bent over upon themselves to provide holding dogs or lips 23. The opposite end of the body of the latch or catch has a bent down portion 24 provided with a hole 24a, most clearly shown in Figs. 6 and 7. Supported in the structure or body portion of the latch, and preferably by a partially tubular part 24b, is a spring-loaded buffer bar or plunger 25, the form of which is most clearly shown in Figs. 5, 6 and 7, wherein it appears that it is provided with a right angled end 25a. Surrounding the said buffer bar or plunger is a coiled spring 25b tending normally to force the end 25a of the buffer bar or plunger against a flange or formation of the door of the camera or other structure as will be hereinafter

described. As shown clearly in the several figures of the drawings, the inner end of the buffer bar or plunger 25 is riveted over to form a head 25c preventing the buffer bar or plunger from being forced too far forward under the influence of the coiled spring 25b. Desirably, also, the buffer bar or plunger 25 while of a rectangular formation in part is of cylindrical form where surrounded by the coiled spring 25b.

10 I have represented particularly in Figs. 2, 3, 6 and 7 the latch or catch as applied to a camera box or casing indicated generally at 26. The said casing is provided with a hinged bed 27 and one or two side arm brackets 28, each of which, 15 in the event two are employed, is attached to an upturned ear 29 upon the camera bed or door portion 27 by means of a shoulder rivet 30. The said camera box 26 is also provided with one or, it may be, two side arm brackets 31 each attached to the camera box 26 by screws 32, 32. 20 The bracket 31, shown in Figs. 2 and 3, is provided with a shoulder rivet 33 received in a groove 34 of the side arm 28, so that the said groove slides along the said rivet when the camera door or bed 27 is being opened and closed, 25 and said rivet rests in a notch 35 when the camera bed or door is all the way open, as shown in Fig. 2. The said side arm 28 is caused to turn in a clockwise direction under the influence of a bent-over spring plate 36 when the camera bed or door 27 is in the all-the-way open position, 30 thus causing the said slot 35 to engage the said shoulder rivet 33. This will prevent the camera bed or door 27 from being closed except when the side arm 28 is pushed to the rear for the purpose 35 of releasing the notch 35 from the shoulder rivet 33.

While I have specifically described the structure of the camera bed or door and the means for holding the same fully open, such means forms 40 no part of the present invention and is merely referred to so that the disclosed application of the invention may be readily understood.

The said latch or catch 20 is attached to the 45 inner face of the top of the camera box or casing 26 by means of screws 37, 37 received in the holes 21, 21 of the latch body part, thus leaving the part of the body portion in advance thereof springable (that is, capable of being sprung away therefrom). The top of the camera box is pierced by a circular opening just above the latch or catch 20 to receive a plunger 38, the head 38a of which is desirably concealed within the leather or like covering 38b of the camera case, but in such a way as to form a slight protrusion indicating where pressure is to be applied by the user. The said plunger 38 is received at its inner end directly upon the flat face 20a of the latch or catch 20 and desirably near the bent down portion 21a, so that pressure thereon will 55 spring the described part of the body portion inward and release the door or bed 27.

It will be observed that when the door or bed 27 of the camera is closed as indicated in Fig. 3, 60 the extreme edge of the lip or lips, dog or dogs 23 engages one face of a flange or formation 39 formed upon the door or bed 27. The said flange or formation is represented as downwardly bent from the edge of the metal portion of the door 27. The other face of the said flange or formation is, when the door 27 is closed, engaged by the outer end of the buffer bar or plunger 25 which is pressed against said flange or formation 39 by the coiled spring 25b. Thus the said 65 flange or formation of the door 27 is firmly en-

gaged at both surfaces or faces thereof, and the door is prevented from rattling.

When the finger-plunger 38 is pushed downward by pressure of a finger of the user of the camera or other structure, the body part 20a of the latch or catch 20, being of suitable resilient material, (that is, being springable) is caused to yield so that the lip or lips, dog or dogs 23 are cleared from the flange or formation 39 of the door. Instantly the force of the coiled 10 spring 25b will cause the buffer bar or plunger 25 to open the door 27 slightly so that it may be readily grasped by the user of the camera or other structure and by him opened into the full-open position shown in Fig. 2. The parts of the 15 latch remain in the position shown in Fig. 2 until the door is closed and when the door is closed the parts will be in the position shown in Figs. 3 and 7, wherein the buffer bar or plunger 25 is shown as thrust all the way back and the lips or 20 dogs 23 as engaging the outer face of the flange or formation of the door 27. Thus the said door is held rigidly in position, preventing any vibration and automatically taking up all wear that may occur in the use of the camera or other 25 structure to which the invention is applied.

The latch or catch herein disclosed is especially adapted for use on photographic cameras where a latch or catch is required that must be easily operated and yet be positive in its action. 30 It cannot be easily jarred open, and yet must at the same time prevent the door of the camera from rattling due to any looseness in the latch parts. All of these requirements are fully met by the latch or catch herein disclosed.

Having thus described one illustrative embodiment of the invention, it is to be understood that although specific terms are employed, they are used in a generic and descriptive sense and not for purposes of limitation, the scope of the 40 invention being set forth in the following claims.

I claim:

1. A combined latch and opening-starter for camera doors and other structures, comprising in combination, a resilient, metallic body portion 45 adapted to be secured at a part only thereof to an inner face of a fixed wall of the structure adjacent the position of the forward edge of the door when tightly closed to said inner face, leaving another part of the body portion capable of 50 being sprung from latching position, and which door has at said leading edge a formation to be engaged by said latch, said body portion having at its said springable part, a part adapted to engage the outer face of said formation, and having a spring pressed plunger to engage the opposite face of said formation, and a finger-actuated plunger mounted in said fixed wall of the structure at such springable part of said body portion of the said latch, whereby pressure 55 against said latter plunger releases said part of the latch from said formation and permits said spring pressed plunger to force open the said door.

2. A combined latch and opening-starter for 60 camera doors and other structures, comprising, in combination, a resilient, metallic body portion adapted to be secured at a part only thereof to an inner face of a fixed wall of the structure adjacent the position of the forward edge of the door when tightly closed to said inner face, leaving another part of the body portion capable of 65 being sprung from latching position, and which door has at said leading edge a formation to be engaged by said latch, said body portion having 70

at its said springable part, integrally formed therewith a lip adapted to engage the outer face of said formation, a spring pressed plunger mounted in the said body portion of said latch 5 so as to engage the opposite face of said formation, and a finger-actuated plunger mounted in said fixed wall of the structure adjacent to and in a position to contact with said resilient body portion at such springable part, whereby pressure against said latter plunger releases the said 10 lip from said formation and permits the said spring-actuated plunger to force open the door.

3. A combined latch and opening-starter for camera doors and other structures comprising, in combination, a resilient, metallic body portion adapted to be secured at a part only thereof to an inner face of a fixed wall of the structure adjacent the position of the forward edge of the door when tightly closed to said inner face, leaving another part of the body portion capable of being sprung from latching position, and which door has at said leading edge a formation to be engaged by said latch, said body portion at its 15 said springable part being bent to form a terminal lip adapted to engage the outer face of said formation, a spring pressed plunger supported by said body portion of the latch and having an end to engage the opposite face of said formation, and a finger-actuating plunger mounted in 20 said fixed wall of the structure adjacent to and in a position to contact with said resilient body portion at such springable part, whereby pressure against said latter plunger releases the said lip from said formation and permits the said spring-actuated plunger to force open the door.

4. A combined latch and opening-starter for camera doors and other structures comprising, in combination, a resilient, metallic body portion adapted to be secured at a part only thereof to an inner face of a fixed wall of the structure adjacent the position of the forward edge of the door when tightly closed to said inner face, leaving another part of the body portion capable of being sprung from latching position, and which door has at said leading edge a formation to be engaged by said latch, said body portion at its 25 said springable part being bent at a plurality of points so as to provide spaced end lips and having an opening therebetween, a spring 30 pressed plunger supported by the body portion of the latch and having sliding movement in said opening, the end of said plunger being adapted to engage the opposite face of said formation, and a finger-actuated plunger mounted in said 35 fixed wall of the structure adjacent to and in a position to contact with said resilient body portion at such springable part, whereby pressure against said latter plunger releases the said lip from said 40 formation and permits the said spring-actuated plunger to force open the door.

from said formation and permits the said spring-actuated plunger to force open the door.

5. A combined latch and opening-starter for camera doors and other structures comprising, in combination, a resilient, metallic body portion adapted to be secured at a part only thereof to an inner face of a fixed wall of the structure adjacent the position of the forward edge of the door when tightly closed to said inner face, leaving another part of the body portion capable of being sprung from latching position, and which door has at said leading edge a formation to be engaged by said latch, said body portion at its 5 said springable part being bent to provide the parts 21a, 22a as continuations of the main body 10 portion and providing terminal lips, the said body portion having an opening 22 between the lateral sides of the bent portion 21a, 22a, a spring pressed plunger supported by said body 15 portion for movement in said opening 22, the 20 said plunger having a formation to engage the opposite face of the formation upon the door, and a finger-actuated plunger mounted in said fixed wall of the structure adjacent to and in a position to contact with said resilient body portion 25 at such springable part, whereby pressure against said latter plunger releases the said lip from said formation and permits the said spring-actuated plunger to force open the door.

6. A combined latch and opening-starter for camera doors and other structures comprising, in combination, a resilient, metallic body portion adapted to be secured at a part only thereof to an inner face of a fixed wall of the structure adjacent the position of the forward edge of the door when tightly closed to said inner face, leaving another part of the body portion capable of being sprung from latching position, and which door has at said leading edge a formation to be engaged by said latch, the said body portion at 30 its said springable part being bent at substantially right angles and again bent at substantially right angles, thereby providing terminal 35 lips in parallelism, but spaced apart, the said body portion having an opening between the lateral sides of the said bent portions, a spring 40 pressed plunger supported by said body portion for movement in the said opening thereof, said plunger having a part to engage the opposite 45 face of the said formation of the door, and a finger-actuated plunger mounted in said fixed wall of the structure adjacent to and in a position to contact with said resilient body portion at such springable part, whereby pressure against said latter plunger releases the said lip from said 50 formation and permits the said spring-actuated plunger to force open the door.

HENRY M. HENDRICKSON.
